(57) **CLAIM**

The ornamental design for a garden irrigation needle connector, as shown and described.

DESCRIPTION

FIG. 1 is a front elevational view of a garden irrigation needle connector comprising the new design.

FIG. 2 is a rear elevational view thereof;

FIG. 3 is a left elevational view thereof;

FIG. 4 is a right elevational view thereof;

FIG. 5 is a bottom plan view thereof;

FIG. 6 is a top plan view thereof;

FIG. 7 is a perspective view thereof; and,

FIG. 8 is another perspective view thereof.

The broken lines shown in the drawings illustrate portions of the garden irrigation needle connector that form no part of the claimed design.
